UNITED STATES PATENT OFFICE.

ALFRED H. EXTON, OF CHICAGO HEIGHTS, ILLINOIS, ASSIGNOR TO EDGAR ALLEN
AMERICAN MANGANESE STEEL COMPANY, OF AUGUSTA, MAINE, A CORPOR-
ATION OF MAINE.

DIPPER-TOOTH.

1,263,874.

Specification of Letters Patent. Patented Apr. 23, 1918.

Application filed September 30, 1914. Serial No. 864,250.

To all whom it may concern:

Be it known that I, ALFRED H. EXTON, a citizen of the United States, and a resident of Chicago Heights, in the county of Cook and State of Illinois, have made and invented certain new and useful Improvements in Dipper-Teeth, of which the following is a specification.

My invention relates to an improved dipper tooth for use in connection with steam or power shovels, and more particularly to a tooth designed for employment with what are generally known and referred to as drag line buckets. Heretofore it has been common practice to form the tooth for such a bucket in one piece, the base being of forged or carbon steel and having a point of tool steel welded thereon. When this point becomes blunt or worn from service, it has been necessary either to discard the entire tooth, or to encounter considerable labor and expense in welding a new point thereon.

The object of my invention is to construct a tooth wherein the general structure of the old form of tooth is preserved in order that it may be substituted for the old structure of tooth in new equipment, or fitted to a drag line bucket already in service, and this without change in the construction or dimensions of the bucket itself or of the tooth, and in which tooth the point may be easily and readily detached from the base when a renewal or repair is necessary, and thereby avoid the scrapping of the base as heretofore, and effecting a considerable saving of metal, which, with the old form of tooth, involved a considerable loss.

A further object of my invention is to so construct the point and base of the tooth that a large part of the strain imposed on the point while the bucket is in use will in turn be directed against the forward end of the base and not upon rivets or bolts which are likely to be sheared off, or broken, and to so shape the engaging parts that they will be locked in their proper relative positions, and so held, without the necessity of employing a large number of said retaining rivets or bolts, or other fastening means.

With these and other ends in view, my invention consists in certain novel features of construction and combinations of parts as will be hereinafter fully described and pointed out in the claim.

In the accompanying drawing, Figure 1 is

a view in side elevation of my improved tooth, the base and point being in their proper relative and assembled positions.

Fig. 2 is an inverted plan view thereof.

Fig. 3 is a sectional view taken on the line 60 3-3 of Fig. 2 looking in the direction as indicated by the arrow.

Fig. 4 is a sectional view taken on the line 4-4 of Fig. 1.

Fig. 5 is a perspective view of the detached point.

Fig. 6 is a perspective view of the forward end of the base, the point being omitted.

Referring to the drawing, it will be seen 70 that the tooth comprises a base and a detachable point, the former being bifurcated to form a short upper jaw 6 and a longer lower jaw 7, each being provided with holes or perforations for the passage of rivets or 75 bolts to secure it to the bucket (not shown), a considerable amount of stock being left forward of the recess 9, forming a nose for the base and insuring a sufficient amount of stock to withstand the strain imposed 80 upon it when the tooth is in service.

The extreme end 10 of the base is in the form of an O. G. curve, in order to form, in effect, a rearwardly extending shoulder 11, and a forwardly extending shoulder 12, 85 to receive the thrust of the detachable point hereinafter referred to.

This nose or forward end of the base is also provided with a recess or pocket extending from the extreme forward end 10 of the 90 base into the lower jaw 7 thereof, the upper wall 13 of this pocket merging into the under side or surface of the jaw 7 at 14, that is, preferably at a considerable distance to the rear of the forward end of the recess 9, 95 this upper wall being inclined from the rear end thereof toward the forward end at which latter end the pocket has a depth equal to the thickness of the forward end of the base, and of a thickness of the rear 100 end of the detachable point hereinafter referred to.

The side walls 15 of this pocket are also inclined, converging toward the bottom, as clearly illustrated in Fig. 4, so that the 105 pocket is not only wedge-shape in the direction of its length, but also trapezoidal in cross-section. It will also be seen that this pocket or recess extends entirely through to the lower side of the jaw 7, and is wholly 110

formed in the nose of the base and in the lower jaw, that is, in those portions of the base containing the greater amount of stock in order to prevent unduly weakening the 5 same.

By reference to Fig. 5 it will be seen that the detachable point 16 is somewhat of the form of a wedge, the upper side or surface 17 inclining from the forward edge 18 to 10 the rear end thereof, and the under side having two different inclines 19 and 20, the rear end or side of the point, which is the thicker, being curved to conform to the shape of the extreme forward end 10 of the base.

15 From this rear thicker side of the point extends a shank 22 wedge-shape in the direction of its length, and trapezoidal in cross-section, and of such dimensions as to nicely fit the pocket formed in the base, the under 20 side or surface 23 of the shank forming a portion or continuation of the under side or surface of the jaw 7 and lying flush therewith, the said shank, as illustrated in Fig. 2, occupying the middle portion thereof. The 25 depth of this shank starts from nothing until at its forward end it is equal to that of the rear or thicker end of the detachable point, the upper side or surface of the shank merging into the upper surface of the point, and 30 the lower or under surface of the shank merging into the under side or surface of the point.

From the foregoing it will be understood that when the base and point are assembled 35 as illustrated in Fig. 1, the shank 22 will largely assist in holding the parts in their locked positions, the wedge-shape cross-section preventing the shank of the point from becoming disengaged from the base in a vertical direction, the shape of the rear side of 40 the point and corresponding shape of the forward end of the base also assisting to this end. To prevent the point from becoming disengaged from the base in a longitudinal 45 direction, I employ a single bolt or rivet 24 which passes through openings formed in the base, and also through a registering opening formed in the shank 22, the ends of the rivet lying flush with the sides of the

base. It will also be understood that when 5 the tooth is in service, the strain imposed upon the detachable point will be transmitted directly to the base, both by reason of the interlocking surfaces of the point and base and also by reason of the long shank 55 extending from the point into the base, the parts, when in their locked positions, in effect acting as one integral casting or forging; furthermore, that in this structure I have retained in the detachable point substantially the outline and contour of the welded point, as well as the outline, contour and dimensions of the base, but at the same time have avoided the objections raised against the old form of tooth, while incorporating therein all the advantages to be obtained from that structure of tooth comprising in part a detachable point.

What I claim is:—

A dipper tooth comprising a supporting 70 base the forward free end of which is curved in outline and downwardly and forwardly inclined, and the under side of which is provided with a centrally located recess or pocket wedge-shaped in cross-section and 75 extending rearwardly from said inclined forward end longitudinally of said base, and the forward end of which recess or pocket extends throughout the length of said inclined free end, said recess being wedge-shaped in outline and tapering from its forward to its rear end; a removable point having inclined walls adapted to contact with the portions of the inclined forward end of said base upon each side of said recess, and a tapering centrally arranged shank wedge-shaped in cross-section adapted to fit within the recess in said base; and a holding member extending through the side walls of said recess and through said shank to thereby secure said removable point and base together.

Signed at Chicago Heights, in the county of Cook and State of Illinois, this 15th day of September, A. D. 1914.

ALFRED H. EXTON.
